US00D340222S

United States Patent [19]

Bedell

[11] Patent Number: Des. 340,222

[45] Date of Patent: ** Oct. 12, 1993

[54] POWER CONVERTER

[75] Inventor: Joel T. Bedell, Merrimack, N.H.

[73] Assignee: ATC Power Systems, Inc.,
Merrimack, N.H.

[**] Term: 14 Years

[21] Appl. No.: 2,210

[22] Filed: Dec. 4, 1992

[52] U.S. Cl. D13/110

CLAIM

The ornamental design for power converter, and shown and described.

DESCRIPTION

FIG. 1 is a perspective view of a power converter showing the new design;

FIG. 2 is a bottom plan view thereof;

FIG. 3 is a side elevational view thereof, the opposite side being a mirror image;

FIG. 4 is a top plan view thereof;

FIG. 5 is an end elevational view thereof;

FIG. 6 is an end elevational view thereof of the opposite side of FIG. 5; and,

FIG. 7 is a perspective view of a power converter showing a second embodiment of the new design, the plan and elevational views being the same as the first embodiment except for the central hole.

FIG. 7
